UNITED STATES PATENT OFFICE.

CONRAD J. KILIAN, OF MILWAUKEE, WISCONSIN, ASSIGNOR OF ONE-HALF
TO DUSTIN ATWOOD, OF SAME PLACE.

GUARD AND STAY FOR ELECTRIC-RAILWAY WIRES.

SPECIFICATION forming part of Letters Patent No. 427,878, dated May 13, 1890.

Application filed December 30, 1889. Serial No. 335,361. (No model.)

To all whom it may concern:

Be it known that I, CONRAD J. KILIAN, of Milwaukee, in the county of Milwaukee and State of Wisconsin, have invented certain new and useful Improvements in Guards and Stays for Electric-Railway Wires; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main objects of my invention are to avoid the danger resulting from broken or crossed wires, to more effectually support the transmission-wires, and to strengthen and stiffen the supports for overhead electric-railway wires.

It consists, essentially, of a guard-wire stretched over the transmission-wire, of depending wires connecting the same with the transmission-wire at suitable intervals, of guard-wires stretched parallel with the transmission-wires at one side thereof, so as to prevent broken wires falling across the same from coming in contact with the transmission-wires, and of certain other peculiarities of construction and arrangement hereinafter described, and pointed out in the claims.

In the accompanying drawings, like letters designate the same parts in the several figures.

Figure 1 represents a pair of the supporting-posts on opposite sides of the railway, the cross-wire, and the arched brace or truss connecting the upper ends of said posts with their connections. Fig. 2 is a cross-section, on an enlarged scale, of the transmission-wires, the supporting and guard wires, and their connections at a point between the posts; and Fig. 3 is a side elevation of the same.

A A are the supporting-posts, formed of joints or single pieces of iron pipe or other suitable material possessing the requisite strength, and set in pairs—one on each side of the railway—as shown in Fig. 1.

B is a cross-wire or cable connecting the upper ends of each pair of opposite posts, and provided with suitable insulation.

C C are arched cross braces or trusses, which may be conveniently formed of gas-pipe, angle or T rails, which are inserted at the ends in mortises formed for their reception in the upper ends of the posts A A, or in blocks a a attached thereto for the purpose.

D D are depending wires or hangers attached at their upper ends to the arched braces C C and at their lower ends to the cross-wires B B, and provided with suitable insulation.

E E are the transmission-wires, which serve to conduct the electric current from the generator to the electric motors on the cars. They are attached to and suitably insulated from the cross-wires B B, preferably adjacent to the attachment of the hangers D D thereto.

F F are supporting and guard wires stretched over the transmission-wires E E and attached to the trusses C C, which they cross, thereby bracing the same laterally and the posts to which they are attached.

f f are hangers connecting the transmission-wires E E with the supporting-wires F F at intervals between the several trusses C C, as shown in Fig. 3. They are provided with suitable insulation to prevent the current from being diverted through the same into the supporting-wires F F. The wires F F serve not only to stay the trusses C C, to which they are attached, but also to prevent falling cross-wires from coming in contact with the transmission-wires, and the hangers f f serve not only to sustain the transmission-wires in the proper position between the cross-wires B B, but also to prevent the ends of the transmission-wires falling to the ground in case of breaks at intermediate points between the cross-wires B B, thereby greatly reducing the danger resulting from broken wires to persons and animals passing under the same.

G G are guard-wires stretched parallel with the transmission-wires at the outer sides thereof and a short distance therefrom, being attached to and supported by the cross-wires B B. At intermediate points they are held at the proper distance from the transmission-wires E E by arms g g, attached to the hangers f f, as shown in Fig. 2. These wires, with the overhead guard and supporting wires F F, prevent other wires falling across them from

coming in contact with and taking the current from the transmission-wires E E, thereby avoiding a very great source of danger to life and property.

5 I claim—

1. In an electric railway, the combination, with the supporting-posts and transmitting-wire, of cross-wires connecting the upper ends of opposite posts, cross-braces between said posts, and a guard-wire stretched over the transmitting-wire and attached to said cross-braces, substantially as and for the purposes set forth.
2. In an electric railway, the combination, with the supporting-posts and transmitting-wire, of cross-wires connecting the upper ends of opposite posts, cross-braces between said posts, a guard-wire stretched over the transmitting-wire and attached to said cross-braces, and hangers connecting said transmitting-wire with said guard-wire at intervals between said braces, substantially as and for the purposes set forth.
3. In an electric railway, the combination, with an overhead transmitting - wire, of a guard-wire stretched over and along the same and a guard-wire stretched along at the side of said transmitting-wire, substantially as and for the purposes set forth.
4. In an electric railway, the combination, with an overhead transmitting - wire, of a guard-wire stretched over the same, hangers connecting the transmitting-wire at intervals with said guard-wire, a guard-wire running at the side of and parallel with the transmitting-wire, and arms interposed between said hangers and said side guard - wire, whereby the latter is held at the proper distance from the transmitting - wire, substantially as and for the purposes set forth.
5. In an electric railway, the combination,

with overhead transmitting-wires, their supporting-posts, cross-wires stretched between opposite posts and supporting said transmitting-wires, arched braces placed between said posts over said cross-wires, hangers connecting said cross-wires with said braces, supporting and guard wires stretched over said transmitting-wires and attached to said braces, which they cross, and hangers connecting the transmitting-wires with said supporting-wires at intervals, substantially as and for the purposes set forth.

6. In an electric railway, the combination, with overhead transmitting-wires, supporting-posts placed in pairs on opposite sides of the railway, cross-wires with which said transmitting-wires are connected stretched between the upper ends of said posts, arched braces interposed between said posts above said cross-wires and connected therewith by hangers, supporting-wires stretched over the transmitting-wires and attached to said braces, hangers connecting the transmitting - wires with said supporting-wires at intervals between the braces, guard-wires stretched at the outer sides of the transmitting-wires parallel therewith and connected with the cross supporting-wires, and arms interposed between said guard-wires and the hangers at intervals between the cross supporting-wires, whereby said guard-wires are held at the proper distance from said transmitting-wires, substantially as and for the purposes set forth.

In testimony that I claim the foregoing as my own I affix my signature in presence of two witnesses.

CONRAD J. KILIAN.

Witnesses:

ARTHUR W. ENSOR,
CHAS. L. GOSS.
